United States Patent Office

Des. 225,646
Patented Dec. 26, 1972

225,646

SUBSCRIBER TERMINAL CONSOLE

Peter P. Klepa and Thomas J. Hermann, Los Angeles,
Calif., assignors to Hughes Aircraft Company, Culver
City, Calif.

Filed July 6, 1971, Ser. No. 160,253

Term of patent 7 years

Int. Cl. D14—02

U.S. Cl. D26—5

FIG. 2.

FIG. 1.

FIG. 3

FIG. 4

FIG. 5

FIG. 1 is a perspective view of a subscriber terminal console showing our new design;

FIG. 2 is a front elevational view thereof;

FIG. 3 is a top plan view thereof;

FIG. 4 is a rear elevational view thereof; and

FIG. 5 is a left side elevational view thereof.

We claim:

The ornamental design for a subscriber terminal console, substantially as shown.
